UNITED STATES PATENT OFFICE.

JOSEPH P. EVANS, OF HAZLETON, PENNSYLVANIA.

IMPROVEMENT IN MACHINES FOR WASHING COAL.

Specification forming part of Letters Patent No. 21,559, dated September 21, 1858.

To all whom it may concern:

Be it known that I, JOSEPH PRIESTLY EVANS, of the borough of Hazleton, in the county of Luzerne and State of Pennsylvania, have invented a new and Improved Automatic Machine for Washing Coal; and I do hereby declare that the following is a full, clear, and exact description of the same, reference being had to the accompanying drawings, making part of this specification.

Figure 1 is a front view of the machine and a section through one of the chambers or chutes over the corrugated bottoms of which the coal passes to be washed. Fig. 2 is a vertical section of same at the line 1 1 of Fig. 1. Fig. 3 is a top view of one of the corrugated bottoms of the chambers or chutes through which the coal passes in the act of being washed.

Similar letters in the figures refer to corresponding parts.

The nature of this invention and improvement consists in washing and separating the dirt, slate, and other extraneous substances from coal by causing it to be subjected to the action of jets of water while slowly descending over an inclined corrugated surface upon which its movement is regulated by adjusted weighted tappets, and at the lower end of which are formed openings and slits for the escape of the refuse stuff and slate, and subsequently passing it over another surface in continuation of the corrugated one in which is formed a slot transverse to the course of the descending coal to allow the separation and discharge of any dirt or other foreign matter from the coal that may have passed the opening and slits above.

To enable those skilled in the art to make and use my invention, I will proceed to describe the construction and operation of the same.

The cylindrical sieve A, into one end of which the coal to be cleansed is first introduced, is formed of a series of metallic skeleton heads secured on an inclined shaft turning in boxes secured to the frame B, which frame may be formed of any suitable size, strength, and material to contain and support the several parts of the machine. The sieve portions of the periphery of the cylinder between the skeleton heads are formed of sieve-wire of different-sized meshes or degrees of

fineness, the upper section A' being of finer meshes than the next one A², and the last or lowermost one A³ being the coarsest and sufficiently large to admit the largest-sized lumps to pass through its interstices. Below this cylindrical sieve is constructed a series of inclined-bottomed chutes C, alike in every respect, one being situated under each section of the sieve A. The sides and front ends of these chutes are made vertical, and segmental scallops or spaces are formed in the sides to admit the periphery of the sieve coming within a short distance of the rear portion of the inclined bottoms of the same, which inclined rear portions of the bottoms consist of metallic plates C', equal in extent to the diameter of the cylinder, while the remaining forward portions consist of corrugated plates C², arranged with the apex of their corrugations on a line with the plates C' and terminating immediately below the end piece of the chute C, the lower portions of the corrugations being cut off at obtuse and acute angles, respectively, with their lower and upper parts at the point where they terminate in front, so as to form right-angled triangle-shaped openings C³ between them, and curved plates D, which are secured to the forward ends of the chutes and extend backward under them at an inclination of twenty-five degrees with the corrugated bottoms of the chutes, through which openings D the dirt and refuse matter are allowed to pass and be discharged over the curved plates D. Small slits D' are also formed in the lower parts of the corrugations to admit the passage of any thin pieces of slate that may be contained in the coal through them.

Immediately above the triangular openings C³ are suspended on a horizontal shaft E, below the front end piece of the chute C, a single or a series of metallic tappets E', placed parallel with each other and the required distance apart to prevent coal passing between them, and having secured near their lower ends a series of rods F, extending outward from their front surfaces at right angles thereto, which rods are inserted through openings in the centers of spherical or other formed weights G. These weights are capable of being moved on the rods F nearer to or farther from the tappets E', so as to regulate the resistance they exert to the passage of the coal under them.

In continuation of the corrugated bottoms of the chutes C and in front of the same are arranged a series of other inclined chutes H, which, like the other parts described over which the coal passes, are made of metal or other suitable material, being turned up slightly at their sides to prevent the escape of the coal over the same, and provided with a narrow slot I across the same midway between its front and back ends, from which slot I extends an inclined chute K, of a precisely-similar character, running backward under the rear part of the chute H at an angle of about twenty-five degrees (more or less) with the bottom of the same in such a manner as to conduct any dirt or refuse stuff that may have passed with the coal over the triangular openings D and slits D' under the tappets E', and over the turned-up edge at the top of the chute H, and discharge the same into any convenient receptacle L, into which is also conveyed the dirt and other extraneous matter passing over the curved plates D. A short distance above the inclined sieve-cylinder A is arranged a water-reservoir M, from the bottom of which extends a series of vertical pipes N, one for each chute C, provided with cocks O near their upper ends, and attached at their lower ends to the centers of horizontal pipes P, arranged at right angles to the same immediately over the lower parts of the corrugated bottoms of the chutes and also at right angles to them. The horizontal pipes P are perforated with round or other formed openings on the lower parts of their periphery, the area of the whole of the perforations being much less than the bore of the pipe N, so as to give force to the water discharging therefrom in such a manner as to cause the water thus escaping to be ejected in jets, forced at acute right and obtuse angles with the bottoms of the chutes C, over which the coal passes, so as to enable these jets of water to strike the under, upper, and, in fact, all parts of the coal as it passes under the same in its descent.

The operation is as follows: The coal to be washed is conveyed, through a hopper or other convenient means, into the upper end of the sieve-cylinder A, to which a revolving motion is previously given by any convenient power. This will cause the coal to gradually descend in the sieve-cylinder and the lumps of coal of less size than the respective interstices in the portions A' A² A³ to pass through the same and to descend onto the bottoms C' of the upper parts of the chutes C and over the inclined surfaces of the same and the corrugated bottoms C² of the said chutes C next in continuation. As it passes over these latter it is subjected to the action of the jets of water from the horizontal pipe P, as before stated, which cleanses it of nearly, if not quite all, of its dirt and other extraneous matter, which, after its separation, passes down in the bottoms of the corrugations under

the coal and off through the triangular openings C³ and slits D' at the lower end of the same into the reservoir L below, from which it can be conducted to any desired point. During this washing process the coal is temporarily detained in its descent or caused to slightly accumulate by the tappets E', whose resistance to its progress is regulated by the weights G, and after this the coal passes off over the edge of the turned-up end of the chute H and under the tappets E', and in its descent over the lower chute H passes over the transverse slot I in the same, through which any refuse stuff that may still remain in the coal will pass and be conducted into the common reservoir L, from which it may be conducted, as before stated, and again subjected to a further operation, if desired, with a view of extracting any valuable matter that it may contain.

During the descent of the coal over the corrugations in the bottom C² of the chute C the thin pieces of slate mixed with the same will be caused to descend into the corrugations with their edges resting on the angular bottoms of the said corrugations, and when these thin pieces of slate reach the slits D' they will, from being on edge, be caused to freely pass through the same. In this simple manner a complete separation of the dirt and other refuse matter from the coal is effected, the latter being discharged from the machine in a perfectly washed and cleaned state, and its movement from the time of its entrance to its exit from the machine being automatic.

What I claim as new, and desire to secure by Letters Patent, is—

1. Forming a series of slits D' at the lower ends of the corrugations C² next the triangular openings C³, so as to enable the thin pieces of slate to discharge themselves automatically through them, substantially as described.

2. The combination and arrangement of a tappet or tappets E' with and in the relation to the corrugated bottoms C² of the chutes C and the slits D' and triangular openings C³ at the lower ends of the same, over which they are suspended, as set forth, the said tappet or tappets being provided with adjustable weights G to regulate their resistance to the coal, substantially in the manner and for the purpose before described.

3. The arrangement of the upright pipe N and right-angled perforated pipe P at its lower end in the relation to the corrugated bottoms of the chutes described, said perforations being formed on the lower portion of its periphery, as stated, for subjecting the coal to a thorough washing in its descent, as herein set forth.
